WALTER F. GORDON, OF DALLAS, TEXAS

CIGARETTE MAKING MACHINE

Application filed March 10, 1932. Serial No. 597,893.

This invention relates to cigarette making machines of the type wherein a spiral conveyor is used for conveying tobacco into and through a tube around which a cigarette paper may be wrapped, the machine being especially adapted for individual or personal use.

The tobacco used in making cigarettes is of three general classes known usually by the terms "granular", "crimp cut" and "shredded". Granular tobacco is in the form of small grains of more or less even size and should be free from pulverized or dust tobacco for cigarette making. Crimp cut is tobacco which is cut to provide strips or flat thread like portions greatly shortened by crimping. In both of these forms the individual pieces of tobacco are usually of proper size for use in making cigarettes and, when thus of proper size, must not be subjected to any further comminution, whether by grinding or cutting, tending to produce tobacco dust.

One object of the present invention is to provide an improved cigarette making machine of this class wherein a conveyor and tube are used and in which the conveyor is so constructed as to properly feed granulated and crimp cut tobaccos into and through the tube without grinding or cutting the tobacco and thus producing undesirable dust.

Shredded tobacco is in the form of quite long thread like pieces and these pieces are inclined to mat together so that proper feeding through the tube of a cigarette machine is hindered and it is, in practice, impossible to make cigarettes in the previous machines if this type of tobacco is employed.

A second important object of the invention is to provide an improved cigarette machine of this class wherein shredded tobacco may be used for making cigarettes, the tobacco being cut by a special arrangement of spiral conveyor into proper lengths to feed freely through the tube and into the cigarette wrapper.

Some tobaccos are sold which are mixtures of two of the above kinds or even of all three. With such mixed tobaccos it is obvious that only those pieces which are too large to feed

properly in the making of a cigarette should be cut up.

A third important object of the present invention is to provide an improved form of cigarette making machine wherein pieces of tobacco of proper size to feed freely through the tube will be conveyed through said tube without further comminution while pieces too large to feed freely will be cut by the conveyor means into proper sizes for free feeding.

With the foregoing objects as paramount, the invention has particular reference to its salient features of construction and arrangement of parts, which will become manifest as the description proceeds, taken in connection with the accompanying drawing, wherein:

Figure 1 is a perspective view of the preferred type of cigarette making machine in which the invention is embodied.

Figure 2 is a detail view of the axis or mandrel constituting the body of the conveyor used herein.

Figure 3 is a view of the body of the conveyor showing the peculiar type of flight spirally wound thereupon.

Figure 4 is a fragmentary detail view in perspective.

Figure 5 is a fragmentary view of the barrel or conveyor casing showing the conveyor in longitudinal cross section.

Figure 6 is a detail view showing the transverse section of the conveyor flight.

Figure 7 is a view in vertical cross section showing the machine illustrated in Figure 1 and showing the assembly of certain parts of the invention.

In proceeding more in detail, it may be stated that the present invention contemplates the use of an improvement over conventional types of flight conveyors which are usually comprised of a strip of material spirally wound upon a body and of uniform thickness in cross section. These conveyors are not possessed of a definite cutting edge and consequently are not capable of cutting into predetermined lengths shreds or like material of any character.

In actual practice, unless the flight of the conveyor is provided with this cutting edge,

shredded tobacco has a tendency to entwine itself about the body and will not advance through the barrel or casing in which the conveyor operates. Material in the nature of tobacco in shreds or long strands will not make into a cigarette unless these strands can be fed into a confined enclosure such as a paper tube and it has been found that this cannot be done satisfactorily except by cutting the shreds into predetermined lengths to prevent the same from becoming entwined about the conveyor.

The conveyor element used in this invention consists primarily of a rod 1 of any suitable material shown in Figure 2 and the winding 3 whose cross section is preferably that shown in Figure 6. Particular notice will be taken that when operatively applied to the mandrel or body 1, the flat base *a* of the flight 3 rests flush against the cylindrical surface of the mandrel. In being so applied, the spiral face *b* of the flight will lie at an angle relative to the axis of the mandrel 1 while the opposed surface *c* will lie at a more acute angle relative to the axis of the mandrel.

It is to be noted that the face *b* of the flight 3 is at such an angle to the body 1 that it forms, with the body, a spiral pocket so that material forced forwardly by the rotation of the conveyor will not tend to be thrown outwardly from the body but, on the contrary, will be urged toward the body from the outer parts of the flight. Thus granulated and crimp cut tobaccos will be urged away from the cutting edge of the flight and will suffer no comminution as they are conveyed along. However, this will not interfere with the cutting action of the conveyor on shredded tobacco since the lengths of the pieces which are too long for feeding is such that they will project into the path of the edge of the flight and be thereby cut into suitable lengths for such feeding.

Referring specifically to the mode of application of the invention, it will be noted in Figure 7 that the barrel 8 is slotted near one end and the sides 9 thereof are turned outwardly against the inner surfaces of a hopper 10, whose sides converge inwardly toward the bottom thereof. Material is therefore fed into the conveyor which advances the same to the outlet end of the barrel 8. Such material as shredded tobacco and the like is cut into predetermined lengths at point *d* in Figure 7 by reason of the fact that the sharp edge of the flight 3 comes into frictional contact with the swedged mouth of the barrel 8 at *d* and no difficulty is encountered in advancing or transporting the material to the outlet end of the barrel 8. The portion *d* of the barrel defines a trap into which the material is forced and compacted to allow the cutting edge of the flight to act thereupon

preparatory to its being advanced through the barrel.

With reference to Figure 1, it will be observed that the hopper 10 is supported upon the base 11, which also carries a small electric motor 12. A wheel 13 is secured to the extended end of the conveyor body which is also shown in Figure 7 and about this wheel is a belt 14, which belt surrounds a pulley 15. In this manner, by pressing the switch button 16, the material placed in the hopper 10 will be speedily issued at the discharge end of the barrel 8. A receptacle 17 is provided to receive surplus or excess tobacco discharged.

A cigarette paper tube, not shown, is placed over the end of the barrel 8 and as the tobacco is fed thereinto, it is moved by the pressure of the advancing material off the end of the barrel. By restraining the movement of the paper tube, the tobacco may be packed into the paper to any desired degree to make a firm cigarette. On the other hand, by allowing the paper to move only by the pressure of the material, a loose cigarette may be produced.

It is also apparent that cigarette papers may be wrapped about the barrel 8 and moistened by means of a small sponge 18 if paper tubes are not available. It is also pointed out that while the machine shown in Figure 1 is operated electrically, the conveyor may be rotated through the medium of a suitable crank.

Manifestly, the construction shown is capable of some modification and such modification as is considered within the scope and meaning of the appended claims is also considered within the spirit and intent of the invention.

What is claimed is:

1. A cigarette making machine including a barrel having a material receiving opening adjacent one end, and a conveyor for cutting and transporting shredded tobacco in the manufacture of cigarettes and arranged to operate in said barrel, said conveyor comprising a cylindrical body having a knife edged strip of material spirally wound thereupon and whose operative diameter equals the inner diameter of said barrel whereby to afford a cutting surface for said tobacco during transportation thereof through said barrel.

2. In a cigarette making machine, a tobacco conveyor having a central body and a spiral flight extending along said body, said flight having its forward face inclined at an acute angle to the body to form a spiral pocket extending along the body whereby material carried forward by the flight is urged inwardly toward the body, and a barrel through which the conveyor extends, said flight having at least a portion of its edge sharpened to cut tobacco caught between the barrel and the conveyor edge.

3. In a cigarette making machine, a tobacco conveyor having a central body and a spiral flight extending along said body, said flight having its forward face inclined at an acute angle to the body to form a spiral pocket extending along the body whereby material carried forward by the flight is urged inwardly toward the body, and a barrel through which the conveyor extends, said barrel having an opening extending along the upper side thereof adjacent its rear end to form a tobacco receiving opening and having its forward portion forming a tube, said flight having at least a portion of its edge sharpened to cut tobacco caught between the tubular portion of the barrel and the conveyor edge.

4. In a cigarette making machine, a tobacco conveyor having a central body and a spiral flight extending along said body, said flight having its forward face inclined at an acute angle to the body to form a spiral pocket extending along the body whereby material carried forward by the flight is urged inwardly toward the body, and a barrel through which the conveyor extends, said barrel having an opening extending along the upper side thereof adjacent its rear end to form a tobacco receiving opening and having its forward portion forming an imperforate tube, said flight having at least a portion of its edge sharpened to cut tobacco caught between the tubular portion of the barrel and the conveyor edge, the rear of the tubular portion of the barrel being flared upwardly to provide a mouth cooperating with the sharpened edge of the flight to cut tobacco into short lengths.

In testimony whereof I affix my signature.
WALTER F. GORDON.
